UNITED STATES PATENT OFFICE.

LOUIS B. ALLAIN, OF SEATTLE, WASHINGTON.

PROCESS FOR MANUFACTURE OF LIQUID-CONTAINERS.

1,197,994.

Specification of Letters Patent. Patented Sept. 12, 1916.

Application filed September 1, 1915. Serial No. 48,421.

To all whom it may concern:

Be it known that I, LOUIS B. ALLAIN, a citizen of the United States, residing at Seattle, in the county of King and State of Washington, have invented certain new and useful Improvements in Processes for Manufacture of Liquid-Containers, of which the following is a specification.

The object of this invention is to improve the art or manufacture of liquid containers from fibrous material, such as paper pulp, and produce the same with transparent or translucent wall portions to enable the contents to be observed.

Apparatus for accomplishing the above referred to operation is illustrated in the accompanying drawings in which—

Figure 1 is a transverse vertical section of apparatus whereby my invention may be effected. Fig. 2 is a horizontal section taken substantially through 2—2 of Fig. 1. Fig. 3 is a front elevational view of a container in the form of a milk bottle such as may be produced in accordance with the present invention. Fig. 4 is a vertical transverse sectional view of the same. Fig. 5 is a detail sectional view through 5—5 of Fig. 4. Fig. 6 is a view similar to Fig. 5 to illustrate a slight modification. Fig. 7 is a fragmentary perspective view of one of the members of the mold shown in Figs. 1 and 2.

The receptacle produced by the present invention is in the nature of a milk bottle, Figs. 3 and 4, having its body composed of a peripheral wall A of paper pulp with an opening B therein closed by a sheet C of transparent or semi-transparent material which is introduced into and has its edges embedded in the surrounding plastic pulp material while the bottle wall portion is being produced. Such wall is furthermore formed with a rabbet D in the mouth and circumferential groove E near the lower end for the reception of the bottom F which is inserted after the body has been removed from the molding machine.

Referring particularly to Figs. 1 and 2, 10 and 10¹ represent mold members having concave inner faces 11 (Fig. 7) and parallel side faces 12. These members are fitted between a cap plate 13 and a base plate formed of separable elements 14 and 14¹. Said mold members are guided for movements radially of the mold axis by rods 15 which slide in guides 15¹ provided on the machine frame. The inner faces 11 of said members are cor-

rugated by providing the same with substantially vertical grooves 11¹ and having attached thereto a sheet 16 (Fig. 7) of fine wire gauze or an equivalent through which the liquid portion of the pulp is forced to escape by the grooves 11¹ when the pulp material is subjected to pressure.

Intermediate the adjacent mold members are guide or wall members 17 having their sides 17¹ arranged in angular relations and in planes parallel to the faces 12 in proximity thereto of said mold members. Like the latter, said wall members are constrained to be moved in radial directions by rods 18 movable in guides 18¹ on the frame. Two of said wall members at diametrically opposite sides of the mold are fixedly secured to or formed integral with the respective elements 14 and 14¹, the inner faces of which are provided with semi-circular openings of a size to accommodate the core to be presently described. Said mold and wall members are caused to be moved radially toward and from the center of the mold by means such as fingers 19 and 20 of the members engaging in cam slots 19¹ and 20¹ of a disk 21 which is journaled on a bearing 22 of the machine frame. As shown, this disk is given reciprocatory rotary motion by means of a connecting rod 21¹ from a crank wheel 23¹ mounted on a shaft 23 which is driven by bevel gears 23², 24¹ and 25¹ from shaft 25 which, in turn, is driven by bevel gears 25² and 26¹ from a power driven shaft 26.

The core of the mold comprises two arcuate members 27 having angular shaped inner faces 27¹, as shown in Fig. 2, and two members 28 and 29 having angularly disposed side faces which are juxtaposed with the faces 27¹ of the other core members. The member 28 has an arcuate outer face 28¹ which is arranged to be coextensive with the outer peripheral surface of the members 27 when the core is in operative condition. The other member 29 has its upper and lower portions, indicated by 29¹, similarly arranged, but intermediate thereof is an offset face 29² which protrudes outside of the periphery of the remainder of the core when in operative position. Opposing the core face 29² is a hollow block 30 which is movable within a chamber 10² of the mold member 10¹ and yieldingly held in its outer position relative to said member by a spring 31. The face 30¹ which is opposite the core face 29² is provided with perforations 30².

10³ represents a pin extending into a slot 30³ of the block 30 to limit the travel of the latter with respect to the member 10¹. Said core members are supported upon a cross-head 32 and are held thereupon by headed bolts 33 which respectively pass through slots 33¹ provided in the feet 33² of the members. The core members are caused to move radially in and from the mold center 10 through the agency of toggle links 34 connecting the respective members with an upright rod 34¹ which is axially movable through a bore provided in the cross-head 32.

The raising and lowering, as well as the 15 expansion and contraction of the core, are regulated and effected from the shaft 26 by a cam 37, which has two cam-slots, in one of which, 37¹, there operates a roller 32¹ which is attached to the cross-head 32 and 20 in the other cam slot 37² operates a roller 35 which is attached to the rod 34¹. These cam slots are respectively shaped so that in one portion of their revolution, the cross-head 32 and the rod 34¹ are lowered simultaneously 25 but that somewhere during their downward motion the ratio of travel of the rod 34¹ is temporarily augmented sufficiently to contract the core, when they again travel simultaneously to their lowest positions. In their 30 upward movements the cross-head 32 and the rod 34¹ travel simultaneously except that prior to the mold being charged the ratio of travel of the rod 34¹ is augmented sufficiently to entirely expand the core, or this 35 expansion of the core may be only enough at this time to bring the face of the core member 29 outside of the core members 27 and by a supplemental travel of the rod 34¹ the expansion of the core be completed as 40 the mold is contracted.

Above the mold are two cylinders 38 and 38¹ arranged concentrically about the axis of the mold to provide an annular chamber 39 for a similar shaped plunger 40 which 45 is given vertical reciprocatory motion by a yoke connection 41 with the arm 42 of a lever whose other arm 42¹ is connected by a pitman 43 with a crank-wheel 44¹ on a stub shaft 44 which is rotated by means of gears 50 44² and 23³ from the aforesaid shaft 23. The outer of said cylinders has an opening communicating with a feed pipe 45 through which the material is supplied to the mold. Included in said pipe is a gate valve 46 55 which is connected to the lever arm 42¹ so that it is opened and closed as the plunger 40 is actuated by the other arm of the lever to shut or expose the opening into said pipe. By such devices and the proper spacing of 60 the valve 46 from the plunger, it is evident that a predetermined charge of pulp may be supplied into the chamber 39 and thence into the mold cavity below in each cycle of the operation. Besides acting as a valve, 65 said plunger is formed at its lower end with

a depending circular rib 40¹ to serve as a coping element for forming the rim and rabbet of the bottle mouth.

In superposed relation with the mold member 10¹ is a receptacle 47 for sheets 48 of transparent or semi-transparent material such, for example, as paraffined paper. Said receptacle is in the form of a box which is open at the top and having an opening in the front between two relatively narrow flanges 47¹ against which the paper sheets are held by a spring-pressed follower 47². These sheets are successively conveyed from said receptacle to and deposited against the foraminated face 30¹ of the mold block 30 70 by means of a carrier 49 and through the instrumentality of vacuum controlled means. The carrier consists in a hollow body provided with a perforated wall 49¹ and suspended by a link 50 from a lever 51 which is fulcrumed at 51¹, said lever being actuated by a pitman 52 from a crank wheel 24³ on the shaft 24. 75

The carrier is adapted to be lowered from its position in front of the receptacle 47, as 80 illustrated, into a position in front of the block 30 when such block is in its outer position from the axis of the core and, as the block is moved inwardly, the carrier is returned to its former position. The carrier 85 by suction power presently to be described, withdraws one sheet of paper from the receptacle; when the carrier presents the sheet in front of the referred to block, the suction is discontinued in the carrier and created in 100 the block to cause the transfer of the sheet thereto and by which it is held until after the sheet is embraced between the block and the aforementioned face 29² of the core member 29. The referred to suction effects 105 are attained by means of a vacuum, or reduced air pressure, which may be created in any suitable manner and, preferably, through the medium of a reservoir 54, which is connected by a pipe 54¹ at the port 55¹ 110 of a valve casing 55 rigidly connected to the machine frame. Within this casing is a valve comprising two pistons 56 and 56¹ which are connected by a rod 56² to the mold member 10¹ to be actuated thereby. The 115 valve casing 55 has a port 55² opening into the external atmosphere and also has a port 55³ connected by a flexible pipe 57 with a port 57¹ provided in a wall of the mold member 10¹ and also has a port 55⁴ connected by 120 a flexible pipe 60 with an opening 60¹ in the carrier 49. Said wall is also provided with a port 58 opening into the external atmosphere. 125

The action of the sheet-conveying appliances may be explained as follows: With the various parts of the machine in the positions in which they are shown in Fig. 1, a sheet of the transparent material, denoted by 48¹, is clamped between the opposing 130

faces of the block 30 and of the core member 29 while the block 30 is pushed back from its extreme protruding position with respect to the mold member 10¹. Being thus located, the ports 58 and 61 of the member and block respectively, are in register for the admission of air into the block interior, which will occur at approximately the time the air is exhausted from the carrier 49 through the pipe 60 and port 55¹ of the valve casing to draw one of the sheets 48 against the face of said carrier 49. During the beginning of the outward travel of the mold member 10¹ it is, by reason of the spring 31, unaccompanied by the block 30, which will cause the port 58 to become inoperative and ultimately bring the port 61 into register with the port 57¹. When the mold member 10¹ is moved to its extreme outward position, the double piston valve is moved through the agency of rod 56², into position to allow the air to be withdrawn from the interior of the block 30 in order to draw the sheet 48 from the carrier 49, which latter has meanwhile been lowered into position in front of said block 30, and to which carrier air has been admitted by the travel of the double valve through the pipe 60 and port 55². The carrier then ascends to receive another sheet and that attached to the block is carried forward in advance of the same to be clamped between the core part 29 and the block, the spring behind the latter yielding to allow the ports 58 and 61 to again register for the admission of air to release the sheet. The sheet thus held between the core and the block has its edges projecting outside of the perimeters of the faces 29² and 30¹ of the respective parts, as indicated in Fig. 2, so that when the pulp is compressed in the mold cavity, such edges will be incorporated with the material.

In forming a bottle, the members 27, 28 and 29 of the core, are raised on the cross-head 32 by means of the cam wheel 37 into the space within the mold members 10 and 10¹ and guide members 17, and the core is then expanded by means of the cam either fully or at least sufficiently to bring the face 29² of the member 29 coextensive with the outer peripheral surfaces of the members 27. Said mold and guide members then occupy substantially the positions in which they are indicated in Fig. 2 by the broken lines 10^a and 17^a except the member 10¹ which has been moved farther out for the lowering of the carrier 49. Then through the office of its slot 19¹ the mold member 10¹ is moved forward to the position indicated by the broken line 10^a and by means of slots 20¹ the guide members 17 are moved into their full-line positions, Fig. 2, and juxtaposed with the side faces 12 of the mold members 10 and 10¹, which are then in posi-

tion to advance toward the center of the mold; the block 30 being protruded from the associated mold member 10¹ and pressing the sheet 48¹ against the face of the core member 29, thus making a portion of said sheet 48¹ from the fibrous material, which is now ready to admit to the mold. This is accomplished through the lever 42—42¹ which regulates the valve 46 and the plunger 40 to supply a charge of the material into the mold, and which material is subsequently compressed by the ultimate inward movement of the mold members 10 and 10¹ up to their full-line positions, Fig. 2, which is effected by means of the slots 19¹ and the ultimate outward movements of the core members, if not already fully expanded as above explained. The bottle body is thus formed with the sheet 48¹ included therein, the masked portion of the same forming part of the wall; after which the core is contracted and lowered and the mold and guide parts withdrawn through the action of the controlling mechanism therefor applied oppositely to that above described, members 10 and 17 being brought to positions indicated by broken lines 10^a and 17^a and the member 10¹ to a position outside its broken line position, to accommodate the carrier 49. A completed bottle body may then be removed from below so as to enable the machine to produce another, and so on.

The invention will, it is thought, be understood from the foregoing description.

What I claim, is—

1. An improvement in the art of forming articles from pulp, consisting in introducing into a mold a sheet of semitransparent material, retaining said sheet with a portion thereof masked supplying a charge of pulp into the mold, and then subjecting such a charge to a compressive force so that the edges only of said sheet will be embedded in the pulp.

2. An improvement in the art of forming a hollow article with an opening in its peripheral wall which is closed by a translucent sheet, consisting of retaining said sheet in a mold so that a portion of the sheet will be masked, supplying a charge of the plastic material into the mold cavity, and finally compressing said material so that the unmasked portions of the sheet will be embedded therein.

3. An improvement in the art of forming receptacles from pulp and a sheet of transparent material, consisting of temporarily holding the sheet at its central portion between the core and an element of a mold having separable members, then supplying a predetermined charge of the pulp into the cavity of the mold, contracting said mold so as to compress the pulp in the space between the mold and the core, and thereby embed the edges of said sheet in the pulp.

100

105

110

115

120

125

130

4. An improvement in the art of forming from pulp and a sheet of transparent material a hollow article, consisting of compressing the pulp between an expansible core and 5 a contractile mold, said core and mold being provided with members adapted to clamp said sheet therebetween so that the edges of the sheet will be embedded in the pulp and then contracting the core and expanding the 10 mold for the removal of the article.
5. An improvement in the art of forming from pulp and a sheet of transparent material a hollow article, consisting of compressing the pulp between a core and a mold, said 15 core and mold being provided with members adapted to clamp said sheet therebetween so that the edges of the sheet will be embedded in the pulp.
6. An improvement in the art of forming 20 hollow articles from fibrous material, consisting in first introducing into the form a sheet of the non-opaque material so that a portion of the sheet will be masked between external and internal members of said form,
- 25 second, supplying a charge of the fibrous material into the form, and third, subjecting

said fibrous material to pressure so that the unmasked portions of said sheet will be incorporated with the fibrous material.

7. An improvement in the art of manufacturing a hollow article in a form from pulp, consisting in introducing into the form a sheet of non-opaque material so that a portion of the sheet will be masked, next supplying into the form a charge of the 35 pulp, and then subjecting such charge to a compressive force so that the unmasked portions of the sheet will be united with said pulp and the masked portion constitute a transparent part of the wall. 40

8. An improvement in the art of forming articles from pulp, consisting in introducing into a form a sheet of semi-transparent material, supplying a charge of pulp into the form, so as to embed the outer portions only 45 of such sheet within the pulp.

Signed at Seattle, Washington, this 18th day of August, 1915.

LOUIS B. ALLAIN.
